FIG. 4. James B. Willis, Inventor

By J. B. Thomas

Attorney

UNITED STATES PATENT OFFICE.

JAMES B. WILLIS, OF ANN ARBOR, MICHIGAN.

TOASTER.

1,014,548.

Specification of Letters Patent.

Patented Jan. 9, 1912.

Application filed November 30, 1910. Serial No. 594,824.

To all whom it may concern:

Be it known that I, JAMES B. WILLIS, citizen of the United States, residing at Ann Arbor, county of Washtenaw, State of Michigan, have invented a certain new and useful Improvement in Toasters, and declare the following to be a full, clear, and exact description of the same, such as will enable others skilled in the art to which it pertains to make and use the same, reference being had to the accompanying drawings, which form a part of this specification.

My invention relates to an improvement in toasters, shown in the accompanying drawings and more particularly pointed out in the following specification and claims.

The object of my invention is to lower the cost of manufacture by simplifying the construction and by reducing the number of parts heretofore found necessary in this type of toaster.

Other advantages and improvements will hereafter appear.

In the drawings accompanying this specification:—Figure 1 is a perspective view of the toaster. Fig. 2 is a detail view of the end of one of the standards showing the tongue by which it is secured to the base plate. Fig. 3 is a detail perspective view of one of the standards engaged with a corner of the base plate,—the tongue being indicated in dotted lines in its bent position. Fig. 4 is a cross-sectional view of the base plate shown in Fig. 1. Fig. 5 is a modification in the form of the base plate.

Referring now to the letters of reference placed upon the drawings: A denotes the base plate having a central perforated portion A', its edges up-turned to form a flange A².

B are cross-standards rising from the four corners of the base plate tapering in a pyramidal form having a flat top B' to support a kettle or other vessel which it may be desired to heat. The standards are engaged to the base by the tongues b, projecting through slots a' provided for their reception.

C is a bolt or rivet engaging the cross-standards at the point of intersection.

D are wire racks shaped to receive and support the bread to be toasted and bridging the openings between the standards,—the ends of the wire being engaged therewith.

In Fig. 5 the base plate A is circular in

form and upwardly convex, as indicated at a,—the shape having a tendency to direct the rays of heat toward the center of the toaster from which point they are more evenly distributed to the surrounding pieces of bread supported on the several wire racks.

It will be seen that I have dispensed with the usual cone-shaped heat radiator heretofore found necessary in toasters of this type and have thereby materially simplified the construction and reduced the cost of manufacture. The perforated base plate serves to evenly distribute and direct the rays of heat against the several pieces of bread supported in an inclined position over the same. It will also be seen that the up-turned flanges of the base plate and the unperforated portion adjoining the flange, serves as a tray to catch the crumbs which may fall from the bread in the act of toasting,—the particles being retained by the surrounding flange within the toaster, thereby protecting the stove from the litter of falling crumbs.

Having thus described my invention, what I claim is:—

1. In a toaster, a base plate provided with a plurality of small perforations, standards rising from the base plate and secured thereto, wire racks inclined with respect to the base plate bridging the spaces between the standards, the area inclosed by the standards and wire racks above the base plate being entirely free and unobstructed, whereby the bread when placed on the racks may be directly exposed to rays of heat rising from the base plate.

2. In a toaster, a base plate, inclined cross-standards rising from the base plate, the intersecting upper portion of the same being formed parallel with the base plate, bread racks secured to said standards bridging the openings between the same, said base plate provided with a plurality of small perforations only for the passage of heat, the area inclosed by the standards and several bread racks and between the base plate and horizontal portion of the standards being free and unobstructed for the uninterrupted passage of the heat rays to toast the bread, substantially as described.

3. In a toaster, a base plate slightly convex having a central portion provided with a plurality of small perforations; a pair of intersecting cross standards rising from opposite sides of the base plate, means for

securing said standards together at the point of intersection, wire bread racks bridging the openings between the standards forming a central inclosure surrounding the perforated portion of the base plate, the space enclosed by said bread racks being entirely free and unobstructed for the passage of the heat rays through the perforated base to the bread supported on said racks.

10 4. In a toaster, a base plate, standards rising from the base plate and secured thereto, wire racks inclined with respect to the base plate bridging the spaces between said

standards, the area inclosed by the standards and several bread racks above the base plate being entirely open and unobstructed, whereby the bread may be directly exposed to the rays of heat rising from the base plate.

15 In testimony whereof, I sign this specification in the presence of two witnesses.

20 JAMES B. WILLIS.
